UNITED STATES PATENT OFFICE.

HAROLD A. HOUSTON, OF WILKINSBURG, PENNSYLVANIA, ASSIGNOR TO WESTINGHOUSE ELECTRIC & MANUFACTURING COMPANY, A CORPORATION OF PENNSYLVANIA.

RAILWAY VEHICLE.

Application filed June 4, 1927. Serial No. 196,429.

My invention relates to railway vehicles and more particularly to devices for connecting and centering the adjacent ends of the trucks of such vehicles.

5 In railway vehicles in which the cabs or bodies are mounted on a plurality of articulated trucks, excessive nosing and lateral movements of the adjacent ends of the trucks are likely to occur when the vehicles travel 10 over curved or uneven sections of track, if the trucks are loosely connected. On the other hand, if the trucks are connected too rigidly, undesirable stresses in the vehicle and excessive wear of the wheel flanges and 15 rails will result. Therefore, it is desirable to connect the adjacent ends of the trucks in such manner that they will be prevented from moving laterally relative to one another, until subjected to a predetermined 20 force.

One object of the invention is to provide for yieldingly opposing the relative lateral movements of the adjacent ends of the trucks.

25 It is also an object of the invention to provide for steering the truck members of railway vehicles and for centering their adjacent ends.

Other objects of the invention will, in 30 part, be obvious and will, in part, appear hereinafter.

The invention is disclosed in the embodiment thereof shown in the accompanying drawings and comprises the structural features and the combination of elements and 35 arrangement of parts which will be exemplified in the construction hereinafter set forth, and the scope of the application of which will be indicated in the appended claims.

40 For a fuller understanding of the invention, reference may be had to the following detailed description taken in connection with the accompanying drawing, in which:

Figure 1 is a view, in side elevation, of 45 fragmentary portions of a pair of articulated trucks provided with a centering device embodying the principles of the invention;

Fig. 2 is a detailed view, partly in section and partly in side elevation, of a portion 50 of the trucks and the centering device illustrated in Fig. 1;

Fig. 3 is an enlarged top plan view of one form of the centering device; and

Fig. 4 is an enlarged top plan view of another form of the centering device.

In the drawing, a pair of cooperating trucks 1 and 2 are illustrated as having the usual frames 3 and 4 that are journaled upon a plurality of axles 5 which are carried by 60 wheels 6 in a well known manner. The trucks 1 and 2 may be coupled together by a draw bar 6 or by any articulated joint that is secured to the respective end sills 7 and 8 of the frames 3 and 4, the particular type 65 of coupling being no part of the present invention.

In order to restrain the adjacent ends of the trucks from moving laterally relative to one another, they are provided with a centering device 9. The centering device comprises a triangular strut or resistance rocker 10 that is disposed between a seating member 11 which is mounted on the truck frame 3 and a yoke member 12 that is supported in 75 a housing 13 which is mounted on the co-operating truck frame 4.

The resistance rocker 10 may be of any form that will provide sufficient resistance to keep the truck ends centered under normal conditions. The rocker illustrated in Fig. 3 has a rounded bearing portion 14 on one end that is disposed in a seat 15 in the seating member 11, and its other end is formed with a flattened cam-shaped face 16 85 that is adapted to rock on the bearing face 17 of the yoke 12.

Another form of resistance rocker is illustrated in Fig. 4 as having a base provided with two rounded corners 18 and 19 that are 90 disposed in cooperating seats 20 and 21 in the seating member 11. The other end of the rocker is provided with a cam-shape face 22 and is disposed in the bearing face 17^a of the yoke 12^a.

In either form of rocker, the cam-shape end is held in position in the yoke by means of an arm 23, one end of which is pivotally connected to the rocker and the other end of which is pivotally connected to an extension 24 on the side of the yoke.

The required variable resistance to the lateral movements of the adjacent ends of the trucks is provided by holding the cam-

shaped rocker or triangular strut 10 between the seating member 11 and the yoke member 12 under such compression that, by reason of the shape of the rocker, a predetermined force is required to unseat it.

As shown, the body of the yoke member 12 is rectangular in shape and is slidably mounted in an opening in the housing. With a view to making the yoke stronger and retaining it in proper position in the housing, its rear portion is provided with an extension 25 that is slidably seated in an opening in an enlarged portion 26 of the base of the housing.

15 In order to bias the yoke against the cam face of the rocker, a number of springs 27 are mounted in the housing, with their inner ends 28 bearing against a spring support 29 constituting a part of the housing 20 and their outer ends 30 bearing against the inner wall 31 of the outer end of the yoke member.

The supporting members of the centering device are generally mounted on the trucks 25 in such position that the rocker, the yoke, and the springs will be under compression when the trucks are connected by the coupling.

30 In operating a vehicle that is equipped with the invention over level straight sections of track, the centering device will easily correct any tendency to nosing or relative lateral movements of the adjacent ends of the trucks. However, when such a vehicle 35 enters a curved section of track, the leading truck will follow the curvature of the rails and thereby give the adjacent ends of the trucks a tendency to swing out of alignment. Under such conditions, the forces exerted by 40 the relative lateral movements of the adjacent ends of the trucks will be opposed by the resistance of the cam or triangular rocker that is disposed under compression in the centering device. If the curvature of the 45 rails becomes very pronounced, the lateral forces exerted by the ends of the trucks will be increased and will unseat the resistance rocker to a greater or less degree and permit the ends of the trucks to move laterally, thereby preventing derailment or damage to the 50 rails or wheel flanges.

It will be understood that the strength of the springs and the shape of the rocker will determine the point at which the forces 55 exerted by the lateral movements of the adjacent ends of the trucks will overcome the resistance of the rocker and cause it to be unseated. Accordingly, they may be designed to meet the conditions under which 60 they will be operated.

While the illustrated example constitutes a particular embodiment of my invention, I do not limit myself strictly to the details shown, since, manifestly, the same may be 65 considerably varied without departing from

the spirit of the invention as set forth in the appended claims.

I claim as my invention:

1. In a railway vehicle, the combination with a plurality of articulated trucks and means for connecting the trucks, of a centering device comprising a seat mounted on one of said trucks, a yoke mounted on a cooperating truck, and a cam rocker disposed to be interposed between the seat and the yoke. 70

2. In a railway vehicle, the combination with a plurality of articulated trucks and means for connecting the trucks, of a centering device comprising a seat mounted on one of said trucks, a yoke mounted on a cooperating truck, a cam rocker disposed to be interposed between the seat and the yoke, and means for positioning the rocker in the yoke. 80

3. In a railway vehicle, the combination with a plurality of articulated trucks and means for connecting the trucks, of a centering device comprising a seat mounted on one of said trucks, a yoke mounted on a cooperating truck, a cam rocker disposed to be interposed between the seat and the yoke, and a link adapted to connect the rocker and the yoke and center one end of the rocker in the yoke. 90

4. In a railway vehicle, the combination with a plurality of articulated trucks and means for connecting the trucks, of a centering device comprising a seat mounted on one of said trucks, a housing mounted on a cooperating truck, a yoke resiliently mounted in the housing, and a cam rocker interposed between the seat and the yoke. 100

5. In a railway vehicle, the combination with a plurality of articulated trucks and means for connecting the trucks, of a centering device comprising a seat mounted on one of said trucks, a housing mounted on a cooperating truck, a yoke movably mounted in the housing, a cam rocker interposed between the seat and the yoke, and a spring located in the housing and adapted to press the yoke against the rocker. 105

6. In a railway vehicle, the combination with a plurality of articulated trucks and means for connecting the trucks, of a centering device comprising a seat mounted on one of said trucks, a yoke mounted on a cooperating truck, and a heart-shape cam rocker interposed between the seat and the yoke. 115

7. In a railway vehicle, the combination with a plurality of articulated trucks and means for connecting the trucks, of a centering device comprising a seat mounted on one of said trucks, a yoke mounted on a cooperating truck, a triangular resistance rocker interposed between the seat and the yoke, and means cooperative with the yoke 120

125

to retain said rocker seated until subjected to a predetermined force.

8. In a railway vehicle the combination with a plurality of articulated trucks and means for connecting the trucks, of a centering device comprising a seat mounted on one of said trucks, a housing mounted on a cooperating truck, a yoke movably mounted in the housing, and a triangular resistance rocker interposed between the seat and the yoke and means cooperative with the yoke to retain said rocker seated until the application of a predetermined force.

9. In a railway vehicle, the combination with a plurality of articulated trucks and

means for connecting the trucks, of a centering device therefor comprising a seat mounted on one of said trucks, a housing mounted on a cooperating truck, a yoke movably mounted in the housing, resilient means for cushioning the yoke in the housing, a triangular resistance rocker interposed between the yoke and the seat, and a link for connecting the rocker and the yoke, said link being disposed to support the rocker in working relation to the yoke.

In testimony whereof, I have hereunto subscribed my name this 27th day of May, 1927.

HAROLD A. HOUSTON.
